UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME CARRIER AND SUPPORT FOR CARPET LOOMS.

Application filed June 18, 1923. Serial No. 645,954.

This invention relates to a carrier or support for the tube frames which insert the pile yarn in fabrics of the Axminster carpet type.

In certain looms for such fabrics, the tube frames are given a rocking motion to swing or wipe the yarn between the warp threads, in addition to the usual reciprocating vertical movement. It is the general object of 10 my invention to improve the construction of looms of this type by providing a tube frame supporting member or carrier extending across the loom and movable with the yarn tube frame, to support and stiffen the frame during the insertion of pile yarn thereby.

My invention further relates to arrangements and combinations of parts which will be hereinafter described and more particularly pointed out in the appended claims.

A preferred form of the invention is shown in the drawings, in which

Fig. 1 is a plan view of parts of a carpet loom embodying my improvements;

Fig. 2 is a side elevation of the parts shown in Fig. 1;

Fig. 3 is a partial front elevation of a tube frame and carrier, looking in the direction of the arrow 3 in Fig. 2;

Fig. 4 is an end elevation of the parts shown in Fig. 3;

Fig. 5 is a view similar to Fig. 4 but showing the parts in a different position;

Fig. 6 is a perspective view of a middle portion of a tube frame, looking from the rear;

Fig. 7 is a sectional elevation taken along the line 7—7 in Fig. 1;

Fig. 8 is a detail front view looking in the direction of the arrow 8 in Fig. 7, and

Fig. 9 is a detail view of a spring releasing slide.

Referring to the drawings, I have shown certain parts of an Axminster carpet loom of a commercial type, including a frame 10, a lay 11, a reed 12, a front knife 13 and a back knife frame 14, all as usual. A pair of arms 15 projecting forwardly at the opposite sides of the loom provide bearings 16 for a pair of short shafts or studs 17. Tube frame holders 18 are firmly secured to the inner ends of the shafts 17 and receive and

support the ends of each tube frame while the yarn carried thereby is inserted between the warp threads.

The arms 15 are bolted to supports 20 pivoted upon a heavy cross shaft 21 at the rear of the loom. The supports 20 are moved vertically to raise and lower the tube frames by rods 22 connected to suitable actuating mechanism not shown.

Short arms 23 (Figs. 3 and 5) are fixed to the outer ends of the shafts 17 and are connected by links 24 to cam levers 25 (Fig. 2) pivoted at 26 and actuated by connecting rods 27 from driving mechanism not shown. Reciprocation of the rods 27 causes the arms 23 to rock about the axis of the shafts 17 and to give the tube frame supported by the holders 18 a rocking or wiping motion to insert the yarn between the warp threads.

The tube frames and their supporting end brackets are in general of the usual type and each bracket includes a vertically projecting guide or positioning member 30 and a spring 31 which forms a supporting and attaching hook by which the tube frame is connected to one of the transporting chains. When a tube frame is to be released from the transporting chains to permit downward movement thereof by the arms 15, the spring hooks 31 are forced inward away from the transporting chains by slides 32 (Figs. 3 and 9) actuated by levers 33. The outer portions of the levers 33 are formed in arcs of circles concentric with the axes of the shafts 17, so that the levers 33 have operative engagement with the slides 32 in every angular position of the tube frame holders 18. The levers 33 are pivoted at 34 on the supports 20 and are moved simultaneously in opposite directions by links 35 actuated by driving mechanism not shown.

For a complete disclosure of operating mechanism for the parts thus far described, reference is made to the prior patent to Smith and Skinner, No. 186,374, issued Jan. 16, 1877.

A support or carrier 40 is mounted on the tube frame holders 18 and extends across the loom from one frame holder to the other. The carrier 40 is preferably formed of two plates 41 and 42 (Fig. 7) of relatively heavy sheet metal riveted together along the

edges to form a structural member having a substantially diamond shaped hollow section. The upper plate 41 is extended at 43 to form a flange or shelf upon which the rectangular tube 44 of the tube frame is firmly supported.

A plate 45 (Fig. 6) is preferably secured to the rear side of the tube 44 near its middle portion and forms a loop or strap adapted to receive a portion 46 of the plate 41 which projects upwardly into an opening 47 formed in said plate. As the tube frame is deposited in the holders 18, the loop 45 slips easily over the projection 46 and prevents lateral displacement of the tube frame and carrier. The upper edge and corners of the projection 46 and the lower edge of the strap 45 are beveled as indicated in Figs. 7 and 8 to assist in easily assembling the parts. A bar 48 (Fig. 7) may be inserted between the plates 41 and 42 to strengthen the carrier near the point where the opening 27 is made therein.

If desired, the rear plate 42 may be cut off at the ends as indicated in Fig. 1, leaving the longer plate 41 to be attached to the inwardly projecting portions 50 of the tube frame holders 18.

Having described the details of construction of my improved mechanism, the operation thereof will be readily understood. As successive tube frames are presented by the transporting chains to the arms 15 and holders 18, the levers 33 are moved inward 30 to release the hooks 31 from the chains and the arms 15 are moved downward to present the released tube frame to the warp, the tube frame being now firmly supported by the carrier 40. As the tube frame is lowered, the holders 18 and carrier 40 are rocked about the axis of the shafts 17 by the arms 23 and the operating mechanism connected thereto, thereby swinging the tube frame from the position shown in Fig. 4 to that shown in Fig. 5 as the tube frame reaches its lowest position.

The parts are then swung backward to the position shown in Fig. 4, inserting the yarn tubes between the warp threads with 50 a swinging or wiping motion, after which the tube frame is raised slightly above the warp threads. The yarn is then cut by the usual front and rear knives and the tube frame is raised to its original position. The 55 hooks 31 are last released to attach the tube frame to the transporting chains.

The provision of the connecting carrier 40 is found to be of great advantage in determining the accurate movement of the 60 yarn tubes, particularly in modern carpet

looms in which the length of the yarn tube frame has been greatly increased.

Having thus described my invention and the advantages thereof I do not wish to be limited to the details herein disclosed otherwise than as set forth in the claims but what I claim is:—

1. In a pile fabric carpet loom, a yarn tube frame, movable holders for said frame, and a tube frame carrier movable with and connecting said frame holders and engaging and supporting said tube frame substantially throughout its length, said tube frame carrier and said tube frame having portions fixed therein and co-operating by movement 75 in the direction of presentation of said tube frame, by which co-operation said tube frame is definitely secured to said tube frame carrier at a point intermediate its ends. 80

2. In a pile fabric carpet loom, a yarn tube frame, movable holders for said frame, and a tube frame carrier movable with and connecting said frame holders and supporting said tube frame substantially throughout its length, said carrier being formed of two sheet metal plates secured together at their longitudinal edges and bent to form a hollow structure of substantially diamond- 85 shape cross section, one of said plates having a projecting lower edge portion forming a supporting flange for said tube frame. 90

3. In a pile fabric carpet loom, a yarn tube frame, movable holders for said frame, and a tube frame carrier movable with and connecting said frame holders and supporting said tube frame substantially throughout its length, said carrier having a projection near its center of length and said tube frame having a loop adapted to engage said 100 projection when said tube frame is supported by said carrier and to hold said frame from displacement on said carrier. 105

4. In a pile fabric carpet loom, a yarn tube frame, brackets on said frame, attaching springs on said brackets, holders for said frames, sliding members in said holders engaging said springs, and actuating means to move said sliding members to force said springs from operative position. 110

5. A tube frame mechanism as set forth in claim 4, in which means is provided for rocking said frame holders, and in which said actuating means engages said slides in every angular position of said frame 115 holders.

In testimony whereof I have hereunto affixed my signature.

WILLIAM W. ROBERTSON.
